LOUIS COHEN, OF WASHINGTON, DISTRICT OF COLUMBIA

ELECTRIC SIGNALING

Application filed November 17, 1927. Serial No. 233,919.

This invention relates to the art of electric signaling. It has for its object to provide novel methods and means for the reception of signals. Another object is to secure sharp 5 selectivity in the reception of radio signals.

Still another object is the elimination of static and stray disturbances in the reception of radio signals.

In the electric communication art, and 10 particularly in the radio art it is necessary to provide methods and means for selective signaling, and in the present state of the art this is generally accomplished by means of tuning, circuits are provided which comprise 15 concentrated inductances and capacities which are adjusted for resonance. In some cases, a single tuned circuit is sufficient to secure the desired selectivity, and in other cases where a higher degree of selectivity is 20 required, more complicated circuit systems, various combinations of coupled circuits, must be employed. In the reception of radio signals it is now the common practice to use 25 a multi-stage tuned radio frequency amplifier, by which the desired degree of selectivity and amplification is obtained. In all cases, however, the fundamental principle by which selectivity is secured is the same, that is, adjustment for resonance of a combination of concentrated inductances and 30 capacities. In this invention a radical departure is made in the method and means for the selective reception of electric signals.

Broadly, the method consists in the use 35 of a wave conductor, that is, a conductor of distributed inductance and capacity, on which stationary waves are established, the electrical length of the conductor being adjusted to correspond to an odd multiple of 40 one quarter wave lengths of the signals, at the nodal points of the stationary waves thus establishing electrical leaks in the form of resistances or impedances to ground are introduced.

45 When this system is properly adjusted in relation to a particular wave length, the signals of that wave length will be effective in building up a high potential because of the reflection of the waves back and forth on the 50 wave conductor, the reflected wave being in

phase and thus producing a cumulative effect giving a high potential at the open end of the wave conductor. The electrical leaks in this case having no effect whatsoever, since they are connected at nodal points, that is, points of zero potential. In the case, however, of signals of other wave length, conditions are entirely different. In the first place there will be entirely absent the building up process of potential due to reflections, since there will be a shift in phase between incident and reflected waves, and therefore inhibiting the establishment of the stationary waves; and as a further consequence, the connecting points of leaks on the conductor will no longer be at zero potential and therefore the leaks will by-pass the current from the wave conductor before it reaches the extreme end where the detector or amplifier is connected. This system affords therefore an efficient 70 means for discriminating in favor of one particular frequency to the exclusion of all others. It is particularly adapted for the reception of radio signals, affording a simple 75 means to secure the high degree of selectivity desired and necessary as in the case of broadcast reception, for instance.

In the drawings accompanying the application, I indicate a wave conductor system comprising three sections and two leaks. This I find quite sufficient in obtaining the degree of selectivity required in commercial work such as broadcast reception for instance. There is no inherent limitation in the system however, to this particular number of sections and leaks. Additional half wave sections of conductor and additional leaks may be introduced if desired and thus enhance still further the selectivity of the 85 system.

On the other hand, a simplification of the system may be obtained by using only two sections and one leak if a lesser degree of selectivity will suffice, which may well be the case in some practical applications of this 90 system.

Another highly important feature of this system is that it renders reception comparatively free from static and other transient disturbances. The reason for it is inherent 95

in the system. Any electrical impulse, other than the signal for which the wave conductor is in proper adjustment, impressed on the wave conductor will be by-passed by the leaks to the ground, and that before it had a chance to traverse the conductor, and thus develop a wave characteristic corresponding to the wave length for which the system is in adjustment.

10 In order that the invention may be better understood, attention is directed to the accompanying drawings illustrating typical embodiments of the invention and form a part of this specification and in which:—

15 Figure 1 is a diagrammatic view of a transmission system embodying a sectional wave conductor and resistance leaks.

20 Figure 2 is a modification in which the ground return is replaced by a sectional wave conductor.

Figure 3 shows the embodiment of the invention and its application for the reception of radio signals.

25 Figure 4 is a modification of Fig. 3 in which the sectional wave conductor is directly connected to the antenna and a grounded metallic return replacing the several ground connections.

30 Figure 5 shows still another embodiment of the invention in which a continuous wave conductor replaces the sectional wave conductor of the previous diagrams.

35 Figure 6 is an embodiment of the invention in which a double wave conductor coupled to an antenna is shown.

Figure 7 is an arrangement in which a metallic return is employed and a wave conductor coupled to an antenna.

40 Figure 8 is a diagrammatic drawing of an arrangement in which the leaks are shown symbolically to designate any type of an impedance.

45 Figure 9 is a detail drawing showing a mechanical arrangement for the simultaneous movement of all the metallic plates associated with the different sections of the wave conductor.

Figure 10 is a sectional view of the wave conductor and associated flat metal plate.

50 Figure 11 is another sectional view showing a metal conductor surrounding half the coil.

55 In all of the above diagrammatic views corresponding parts are indicated by the same reference characters.

Figure 1 is intended to illustrate broadly the fundamental principle of the invention. A high frequency energy source 1 is connected to ground 2 and terminal 3 of the sectional wave conductor 4, 5 and 6. The points 7 and 8 are separately connected through variable resistances 9 and 10 to ground 2. Each section of the wave conductor is provided with a metal plate 11 which is connected to ground 2 through the lead 30. The distributed in-

ductance of each section 4, 5 or 6, or the capacity to ground of the sections or both are varied until the following relations are obtained.

For sections 4 and 5:

$$f = \frac{1}{2\sqrt{LCl_1}}$$

For section 6:

$$f = \frac{1}{4\sqrt{LCl_2}}$$

Where f is the frequency of the impressed voltage, L and C are the inductance and capacity per unit length of coil in each section; l_1 is the length of section 4 or 5, and l_2 is the length of section 6. By making $l_2 = \frac{1}{2}l_1$ both Equations 1 and 2 are simultaneously satisfied, that is, if the inductance and capacity per unit length are the same in all the three sections, then the last section is to be half the length of the other sections. The variation of the distributed capacity is readily accomplished by varying the separation distances of the grounded metal plates 11 from the coils 4, 5 and 6, and they can be all adjusted simultaneously. Provisions can also be made to vary the inductances, but it seems simpler to vary the capacities. In either case, however, the relations given by Equations 1 and 2 must be satisfied. The reasons for these are as follows:—

If a series of alternate impulses are impressed on one end of a line of distributed inductance and capacity, the other end of the line being open, the impulses are reflected at the open end of the line. If now, the impulses are so timed that alternating impulses occur at time intervals equal to that required for the impulses to travel the length of the line and back, the effect of successive impulses add themselves, and large currents or high voltages may be produced by small impulses.

In the case of an alternating electromotive force acting on an open line, the line resonance condition, that is, the condition for building up a high voltage due to reflection, is secured when the following relation is obtained,

$$f = \frac{V}{4l}$$

Where f is the frequency of the impressed electromotive force V is the velocity of propagation and l is the length of the line. If we designate the inductance and capacity per unit length of line by L and C , the velocity of propagation is given by

$$V = \frac{1}{\sqrt{LC}}$$

and

$$f = \frac{1}{4\sqrt{LCl}}$$

Also, since in all cases of wave motion, the wave velocity V is connected with the wave length λ and the frequency f in the relation given by the formula

5

$$V = f\lambda$$

we get:

10 and

$$V = \frac{1}{\sqrt{LC}} = \frac{\lambda}{4\sqrt{LC}},$$

$$l = \frac{\lambda}{4}$$

15 To realize the condition spoken of above, the line must be one quarter wave length long. It is also evident that by making the distributed inductance and capacity per unit length of conductor large, a wave development may be effected in a short distance of conductor; and this is accomplished in this invention by making the wave conductor in the form of a solenoidal coil wound with very fine wire and making the distributed capacity 20 relatively large by the proximity to the coil to the grounded metal plates 11.

To obtain the results outlined above, it is not at all necessary, however, to limit the length of the wave conductor to one quarter 30 wave lengths; a conductor of any odd multiple of quarter wave lengths will be equally effective in building up a high voltage through line resonance, provided, of course, the resistance losses of the conductor are not 35 too great.

In the arrangement shown in this figure, that is Figure 1, and also subsequent figures, I make use of a wave conductor capable of adjustment for the development of five quarter wave lengths for any frequency of impulse within the range of frequencies for which this system is designed. In this figure, sections 4 and 5 are adjusted for a half wave length each and section 6 is adjusted for a 40 quarter wave length. In this case, nodal points are established at 7 and 8 that is, points of substantially zero potential, and resistance leaks to ground 9 and 10 are connected at these points.

45 In the case, therefore, of an alternating electromotive force of a frequency for which this system is adjusted, a high potential is established at the extreme open end 12 due to so-called line resonance as explained above, and little if any energy is by-passed to ground through the leak circuits 7, 9, 2 and 8, 10, 2, for the reason that the points 7 and 8 on the line are practically at zero potential for that particular frequency. Hence, this 55 method offers a means for securing a high voltage at the point 12 which may be utilized in many ways particularly in the reception of radio signals as described in connection with other figures of this specification.

60 In the case of different frequencies, the

resonance effect is of course absent, and in addition, and this is very important, the points 7 and 8 are no longer nodal points, that is, zero potential points, and hence whatever energy flows on the conductor, most of it is bypassed to ground through the circuits 7, 9, 2 and 8, 10, 2, and little if any energy reaches the extreme open end 12. This method therefore provides a double means for securing selectivity, discriminating with great sharpness in favor of one particular frequency for which this system is adjusted.

70 In Figure 2 a modification is shown in which a return wave conductor 4', 5', and 6' is used, each section of both wave conductors is separately associated with an independent grounded metal plate to effect a variation of the capacity of each section. For the particular frequency for which this system is adjusted, a high potential is established between 75 the points 13 and 14.

80 Figure 3 shows an embodiment of the invention and its application for the reception of radio signals. The antenna 15 connected to ground 2 through the inductance 16 is coupled to wave conductor 4 through the transformer 85 90

25. The received signals acting on the antenna 15 are impressed on the wave conductor through the transformer 25. Sections 4 and 5 of the wave conductor are adjusted by varying the separation distances of the metal plates 11 from the sections of the wave conductor to satisfy for the frequency of the received signal the condition given by Equation 1, and section 6 is adjusted to satisfy the condition given by Equation 2. It is preferable to have sections 4 and 5 identical in every respect, and section 6 of the same form and structure but only half the length of either 4 or 5, and in that case, the same separation of 95 all the metal plates 11 will affect all of the sections in the same way, and hence a simultaneous adjustment could be effected. The metal plates 11 may be connected mechanically and adjustment effected by one movement. It may also be arranged to keep the metal plates 11 fixed and the wave conductor 100 105 110 115 120 125 130 4, 5 and 6 moved with respect to the metal plates. Either arrangement may be made to serve the purpose.

In either case half wave lengths are established on sections 4 and 5 and a quarter wave length on section 6 with nodal points at 7 and 8. An adjustment is also to be made of the resistances 9 and 10. For best results the values of the resistances 9 and 10 must bear a relation to the ratio of the inductance to the capacity of the wave conductor which I have established mathematically, and which can also be determined experimentally.

When the above conditions are fulfilled stationary waves are established on the wave conductor developing a high voltage at the extreme open end 12 which is impressed on the grid 17 of the three electrode vacuum tube 130

detector 20. An amplifier may be added through the transformer connection 19 in the usual way. For signals of different frequencies from the frequency for which this system is an adjustment there is no building up of high voltage at the end of the wave conductor because of line resonance as in the case of the frequency for which this system is in adjustment, and what is even more important, the points 7 and 8 are no longer zero potential points, and hence any current flowing in the conductor is by-passed to ground through the resistance leaks 9 and 10 and therefore, very little finds its way to the terminal 12.

By this arrangement therefore, a sharp discrimination is secured in favor of one particular frequency, that is, high selectivity.

This system is also very effective in preventing any transient disturbances, such as static and others which may act on the antenna to find its way to the detector. Any electric impulse impressed on the wave conductor must traverse the wave conductor before it acquires a wave characteristic corresponding to the electrical characteristic of the wave conductor, but in its passage through the wave conductor most of its energy is by-passed to ground through the leak resistances 9 and 10. for the most effective elimination of static disturbances, it would be more desirable to add one or more sections of wave conductor and a corresponding addition of the resistance leaks to ground.

Figure 4 is a modification in which the wave conductor is connected to the upper point of the loading inductance 16 of the antenna 15 and a common grounded terminal 21 is used, which may be only a wire connection. The two terminals 22 and 23 are connected to grid and filament of a detector or amplifier tube 24 in the usual way.

Since this system possesses a high degree of selectivity, there is no need to employ any tuning in the amplifier and a resistance coupled type amplifier may be used.

Figure 5 shows an embodiment of the invention in which a continuous wave conductor 26 is used and of sufficient length to insure the development of at least five quarter wave lengths, and resistance leaks 9 and 10 connected at half wave length intervals at the points 7 and 8 which are nodal points. A grounded metallic return 21 is used and the system is coupled to the antenna.

The modification shown in Fig. 6 consists in the addition of the variable condenser 28 for tuning the transformer coil 27.

Another embodiment of the invention is shown in Fig. 7 in which a double wave conductor system 4, 5, 6 and 4', 5', 6' is coupled to an antenna and associated with a detector and amplifier for the reception of radio signals corresponding to the arrangement described in connection with Fig. 2.

The embodiment of the invention shown in

Figure 8 differs only from the arrangement shown in Fig. 4 in that the resistance leaks 9 and 10 are replaced by impedances Z_1 and Z_2 which may be in the form of inductances or capacities or any combination of inductances and capacities. It may be observed that in all of the arrangements shown in the various figures, the resistances 9 and 10 may be replaced by impedances, that is, any combination of inductances and capacities, though it is preferable to use resistances. Also in all of the figures the plates 11 may be in bent form to enclose part or most of the coil, thereby increasing the capacities of the coils to ground. Also variable condensers may be used in connection with the antenna and coupling coils in all of the figures.

Figure 9 is a detailed view showing an arrangement for the simultaneous adjustment of the separation distances of the grounded metal plates 11 from the sections 4, 5 and 6 of the wave conductor. The metal plates 11 are all connected to a support 32 which is movable through the screw motion 34, 35 of the rod 33 which is connected to the support 32.

Figure 10 is a sectional view of the wave conductor and flat metal plate in proximity to it, and

Figure 11 is a sectional view of the wave conductor and a bent metal conductor to enclose part of the coil of the wave conductor thereby increasing the distributed capacity of the coil to the ground.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A system for the selective reception of electric signals of a particular frequency which consists in interposing between the source where the signals are received and the detecting means, a sectional wave conductor comprising several sections each of said sections except the last adjusted to a half wave length corresponding to the frequency of the signal, and the last section of said sectional wave conductor adjusted to a quarter wave length corresponding to said signal frequency; also providing resistance leaks connected at the junction points of adjacent sections of said sectional wave conductor and associating with said sectional wave conductor means for detecting said electric signals.

2. A system for selective signaling which consists in causing the signals to pass through a wave conductor before acting on the detector, establishing stationary waves

on the said wave conductor and connecting impedance leaks at the nodal points of the said stationary wave on the said wave conductor.

and capacity electrically associated with the said antenna circuit, the said wave conductor consisting of a long solenoidal coil and having a grounded metal plate in close proximity to the said solenoidal coil, the separation distance between the said grounded metal plate and the said solenoidal coil being adjustable to thereby vary the distributed capacity of the said wave conductor; the inductance and capacity per unit length and the length of the wave conductor being adjusted to insure the development of five quarter wave lengths for the signals desired to be received, establishing a stationary wave on the said wave conductor, impedance leaks connected to ground at the nodal points of the said stationary wave and connecting detecting means to the extreme open end of the said wave conductor.

5. 3. In a system for the reception of radio signals comprising an antenna circuit, a wave conductor of distributed inductance and capacity electrically associated with the said antenna circuit, the said wave conductor consisting of a long solenoidal coil, a grounded metal plate in close proximity to the said solenoidal coil; the inductance and capacity per unit length, and the length of the wave conductor being adjusted to insure the development of odd multiple of quarter wave lengths for the signal desired to be received, establishing thereby a stationary wave on the said wave conductor, impedance leaks connected to ground at the nodal points of the said stationary wave, and detecting means connected to the extreme open end of the said wave conductor.
- 10.
- 15.
- 20.

7. In a system for the reception of radio signals comprising an antenna circuit, a wave conductor of distributed inductance and capacity electrically associated with the said antenna circuit, the said wave conductor consisting of a long solenoidal coil, a grounded metallic conductor partially surrounding said solenoidal coil, the separation distance between the said solenoidal coil and said metallic conductor being adjustable to thereby vary the distributed capacity of said wave conductor, the inductance and capacity per unit length and the length of the wave conductor being adjusted to insure the development of an odd multiple of quarter wave lengths for the signals desired to be received, establishing a stationary wave on the said wave conductor, impedance leaks connected to ground at the nodal points of the said stationary wave, and connecting detecting means to the extreme open end of the said wave conductor.

4. In a system for the reception of radio signals comprising an antenna circuit, a wave conductor of distributed inductance and capacity electrically associated with the said antenna circuit, the said wave conductor consisting of a long solenoidal coil, a grounded metal plate in close proximity to the said solenoidal coil; the inductance and capacity per unit length, and the length of the wave conductor being adjusted to insure the development of odd multiple of quarter wave lengths for the signal desired to be received, establishing thereby a stationary wave on the said wave conductor, variable resistance leaks connected to ground at the nodal points of the said stationary wave, and detecting means connected to the extreme open end of the said wave conductor.

8. In a system for the reception of radio signals comprising an antenna circuit, a wave conductor of distributed inductance and capacity electrically associated with the said antenna circuit, the said wave conductor consisting of a long solenoidal coil, a grounded metallic conductor partially surrounding said solenoidal coil, the separation distance between the said solenoidal coil and said metallic conductor being adjustable to thereby vary the distributed capacity of said wave conductor, the inductance and capacity per unit length and the length of the wave conductor being adjusted to insure the development of an odd multiple of quarter wave lengths for the signals desired to be received, establishing a stationary wave on the said wave conductor, impedance leaks connected to ground at the nodal points of the said stationary wave, the extreme open end of said wave conductor being connected to the grid of a three electrode vacuum tube amplifier. 110
115
120
125

5. In a system for the reception of radio signals comprising an antenna circuit, a wave conductor of distributed inductance and capacity electrically associated with the said antenna circuit, the said wave conductor consisting of a long solenoidal coil and having a grounded metal plate in close proximity to the said solenoidal coil, the separation distance between the said grounded metal plate and the said solenoidal coil being adjustable to thereby vary the distributed capacity of the said wave conductor; the inductance and capacity per unit length and the length of the wave conductor being adjusted to insure the development of an odd multiple of quarter wave lengths for the signals desired to be received, establishing a stationary wave on the said wave conductor, impedance leaks connected to ground at the nodal points of the said stationary wave and connecting detecting means to the extreme open end of the said wave conductor.

9. In a system for the reception of radio signals comprising an antenna, a sectional 130

wave conductor electrically associated with the said antenna, the said sectional wave conductor consisting of several sections, each section except the last one adjusted for a half wave length corresponding to the frequency of the signal received, the last of said sections adjusted to a quarter wave length of the signal received; establishing stationary waves by the received signal on said sectional wave conductor with nodal points at the junctions of adjacent sections; variable resistance leaks to ground connected at the nodal points, and means for detecting the signals connected at the extreme open end of said sectional wave conductor.

10 10. In a system for the reception of radio signals comprising an antenna, a sectional wave conductor coupled to the said antenna, the said sectional wave conductor consisting of three sections, the first two sections being identical and each being adjusted for half wave lengths corresponding to the frequency of the signal to be received and the last section being adjusted to a quarter wave length of the signal received; two variable resistance leaks to ground connected separately at the two junction points of the said three sectional wave conductor, and detecting means connected to the extreme open end of said sectional wave conductor.

20 11. In a system for the reception of radio signals comprising an antenna, a sectional wave conductor electrically associated with the said antenna, the said sectional wave conductor consisting of several sections, each section consisting of a solenoidal coil having a grounded metal conductor in close proximity to it, the separation distance between said solenoidal coil and said grounded metal conductor being variable to effect thereby a variation in the distributed capacity of each of said sections; each of said sections except the last being adjusted for half wave lengths corresponding to the frequency of the signal received and the last of said sections being adjusted to quarter wave length corresponding to the frequency of the signal received, establishing stationary waves by the received signal on said sectional wave conductor with nodal points at the junctions of adjacent sections; variable resistance leaks to ground connected at the nodal points and means for detecting the signals connected at the extreme open end of the said sectional wave conductor.

30 12. In a system for the reception of radio signals comprising an antenna which is coupled to a sectional wave conductor, one terminal of said sectional wave conductor being grounded through a coupling coil and a variable condenser, the said sectional wave conductor consisting of several sections, each section consisting of a solenoidal coil having a grounded metal conductor in close proximity to it, the separation distance between said solenoidal coil and said grounded metal con-

ductor being variable to effect thereby a variation in the distributed capacity of each of said sections, each of said sections except the last being adjusted for half wave lengths corresponding to the frequency of the signal received and the last of said sections being adjusted to quarter wave lengths corresponding to the frequency of the signal received, establishing stationary waves by the received signal on said sectional wave conductor with nodal points at the junctions of adjacent sections; variable resistance leaks to ground connected at the nodal points and means for detecting the signals connected at the extreme open end of the said sectional wave conductor.

70 In testimony whereof I hereunto affix my signature.
